ELEVATOR BUFFER

Herbert E. Brannon, Oak Park, Ill., assignor to
Westinghouse Electric Elevator Company, a
corporation of Illinois

Application May 16, 1931. Serial No. 537,817

5 Claims. (Cl. 187—67)

My invention relates to buffers for retarding elevator cars at their limits of travel and more specifically to buffers of a horizontal type which take up a minimum of space in the pit.

It is customary in elevator practice to provide an oil buffer at each end of the hatchway for engaging the car when it overruns its normal limits of travel, to thereby absorb its kinetic energy and retard it to a smooth stop. The buffers previously used have been of the vertical type and have required a vertical space which is several times that of the useful vertical stroke of the buffer.

The necessary additional space for the lower buffer was sometimes found by sinking it below the bottom of the pit, although this involved considerable expense and trouble, especially when bed rock was encountered. Furthermore, it has sometimes happened that the bottom of the pit was over a subway and it was then impossible to sink the buffer.

In any event, the additional space for the upper buffer must be found above the hatchway and can only be provided at considerable expense. Furthermore, elevators are now being operated at much higher speeds than formerly, and the space required for vertical buffers which are properly designed to stop high-speed cars is much greater than that required for low-speed buffers. Consequently, the difficulty of finding suitable space for placing the buffers is increasing rapidly under modern conditions and must be solved in order to permit progress along other lines.

It is, accordingly, an object of my invention to provide an elevator buffer which will occupy a minimum amount of space in the hatchway.

Another object of my invention is to provide an elevator buffer which may be mounted in a horizontal position in the hatchway.

More specifically stated, it is an object of my invention to provide a horizontal elevator buffer with a receding ram which shall maintain its head constantly in the center of the hatchway as the buffer is actuated.

According to my invention, I mount the cylinder and the piston of my buffer in a horizontal position and provide an actuating mechanism to transmit the vertical motion of the car to the piston which is driven horizontally. The actuating mechanism comprises a pivoted lever which carries a ram slidably mounted thereon. The ram presents a head which is adapted to be engaged by a striker plate on the bottom of the car. Means is provided for withdrawing the slidably ram as it is depressed by the car in order to maintain the head constantly in the center of the hatchway.

The invention itself, however, both as to its organization and its method of operation, together with additional objects and advantages thereof, will best be understood from the following description of a specific embodiment, when read in conjunction with the accompanying drawing, in which:

Figure 1 is a sectional view of my device taken longitudinally through the cylinder and crank case;

Fig. 2 is a side elevational view of my device, the cylinder crank case and one crank member being omitted to show only the ram and its associated mechanism; and

Fig. 3 is an end view showing the slidable ram and its associated mechanism, as indicated by the line III—III in Fig. 2.

The apparatus shown in Fig. 1 comprises a cylinder 11 and an associated crank case 12 supported by suitable feet 13. As shown, this assembly may constitute a compact unitary structure mounted close to the bottom of the pit. For convenience of assembly and inspection, an opening 14 may be provided in the end of the crank case which is closed by a removable cover 15 secured thereto in any conveniently detachable manner.

A piston 21 is slidably disposed in the cylinder 11, and longitudinally extending grooves 22 are cut in the walls of the cylinder to allow the oil to escape past the piston when the buffer is actuated. The size and shape of the grooves 22 are selected according to the buffer characteristics desired. Instead of the grooves, apertures may be provided to permit the oil to escape through the cylinder walls, and an outer shell may be provided to catch the oil and return it to the crank case, if desired.

In the lower portion of the crank-case, a heavy shaft 23 is journaled to support an upwardly-directed crank 24. The upper or free end of the crank 24 is connected to the piston 21 through a heavy connecting rod 26. Since the operation of the device is accompanied by the rotation of the shaft 23 and crank 24 through only a partial rotation of something less than 180°, it is possible to make a very rigid structure by extending the shaft 23 through, and journaling it in both walls of the crank-case. The crank may also be a rigid structure consisting of a pair of crank members 24 extending upwardly from the shaft 23 to support opposite ends of the connecting-rod pin 25.

One end of the shaft 23 protrudes from the crankcase 12 and carries a lever arm or ram car-

riage 31 which is keyed rigidly thereto, as shown in Figs. 2 and 3. The lever or ram carriage may be reinforced by reinforcing members, as shown in Figs. 1 and 2. Slidably mounted on the ram carriage is a ram 32 the free end of which presents a head 33 disposed for engagement by a striker plate 34 on the bottom of the elevator car 35.

As the car descends, its striker plate 34 engages the ram head 33 of the buffer, thereby rotating the ram carriage 31 and the shaft 23 and driving the piston 21 into the cylinder. In order to withdraw the ram head 33 and cause it to remain in alignment with the striker plate 34 in the center of the car, a stationary gear segment 36 is mounted in concentric relation to the shaft 23. The gear segment 36 may be bolted to the side of the crank-case 12 or secured in any convenient manner to prevent rotation. Rack gear teeth 37 are cut integral with the lower end of the ram. A pinion 38 is supported in simultaneous engaging relation to the rack teeth 37 and the gear segment 36. As shown in Fig. 3, the pinion 38 is supported by a shaft 40 extending through crank members 39 keyed rigidly to the shaft 23.

As the car causes the ram carriage to rotate, the shaft 23 and cranks 39 are simultaneously rotated, and the pinion 38 is carried around the gear segment 36 in operative engagement therewith. This action causes the pinion 38 to rotate and draw the ram 32 back on the carriage 31, giving the head 33 a vertical descending movement on the center-line, as shown in Fig. 2, until it reaches its final position represented by broken lines. By making the portion of the pinion 38 which engages the gear segment 36 of a different diameter than that portion which engages the rack gear 37 it may be made to retract the ram 32 at any speed desired.

As the descending car depresses the ram carriage 31 and rotates the shaft 23, the piston 21 is driven back into the cylinder 11, thereby forcing the entrapped oil to escape through the grooves 22 or other passages provided for that purpose. The rate at which the oil can escape limits the speed of rotation of the ram carriage, and retards the car accordingly.

The actuating mechanism for the buffer constitutes a reducing gear, and the stroke of the piston in the cylinder may therefore, be much less than the useful stroke of the buffer. Since the cylinder 11 is itself mounted in a horizontal position, it is apparent that the vertical space occupied by my buffer is but very little more than the useful stroke of the buffer.

After the device has been actuated to stop a car, it may be retracted to its operative position by any suitable biasing means, such as a helical or spiral spring for lifting the ram carriage or rotating the pinion. It is to be understood that my buffer may also be mounted in an inverted position above the elevator hatchway for retarding the car at its upper limit of travel. If desired, the ram may be made in two parts to permit greater flexibility for arranging the compen-

sating sheave and cables. The buffer may be mounted on either side of the hatchway next to the wall and permit still greater freedom and space in the pit.

It will be apparent that I have provided an elevator buffer which, because of its reducing gear and horizontal position, requires a minimum amount of space for installation and operation, which does not require an outer chamber for the oil but utilizes the crank-case space, and wherein the ram is receding and maintains the head constantly under the center of the car.

Although I have shown and described a specific embodiment of my invention, I am fully aware that many modifications thereof are possible. My invention, therefore, is not to be restricted except insofar as is necessitated by the prior art and by the spirit of the appended claims.

I claim as my invention:

1. In a horizontal elevator buffer, a cylinder, means for mounting the cylinder in a fixed horizontal position adjacent to the end of a hatchway, a piston in said cylinder, and vertically actuatable means engageable by an elevator car for moving said piston horizontally, said means comprising a pivoted ram carriage and a retractable ram carried thereby.

2. In combination with an elevator buffer, a pivoted lever for actuating the buffer, a slidably mounted ram and head carried thereby for engagement by a car, and means for withdrawing said head as it is depressed by the car to define a rectilinear path.

3. In combination with an elevator buffer, a pivoted lever for actuating the buffer, a slidably mounted ram and head carried thereby for engagement by a car, means for withdrawing said head as it is depressed by the car to define a rectilinear path, and speed-reducing mechanism interconnected between the lever and the buffer, whereby the stroke of the buffer may be short, as compared with the useful stroke of the ram head.

4. In a horizontal elevator buffer, a unitary structure comprising a cylinder, a crank-case and supporting means, said crank-case serving as an oil reservoir for the cylinder, a piston in said cylinder, a pivoted lever adapted to be disposed in an elevator hatchway, and speed reducing actuating mechanism in said crank case operably responsive to rotation of said lever for driving the piston into the cylinder.

5. In a horizontal elevator buffer, a unitary structure comprising a cylinder, a crank-case and supporting means, said crank-case serving as an oil reservoir for the cylinder, a piston in said cylinder, a pivoted lever adapted to be disposed in the elevator hatchway, speed-reducing mechanism interconnected between the lever and the piston for driving the piston into the cylinder when the lever is depressed, and means for reducing the effective length of said lever as it is depressed, whereby a rectilinear path is described.
